(57) **CLAIM**

The ornamental design for a adaptor for holding a threading device, as shown and described.

DESCRIPTION

FIG. 1 is a perspective view of and adaptor for holding a threading device showing my new design;

FIG. 2 is a side elevational view thereof taken in the direction of arrow 2 in FIG. 1;

FIG. 3 is a side elevational view thereof taken in the direction of arrow 3 in FIG. 1;

FIG. 4 is a side elevational view thereof taken in the direction of arrow 4 in FIG. 1;

FIG. 5 is a front elevational view thereof taken in the direction of arrow 5 in FIG. 1; and,

FIG. 6 is a rear elevational view thereof taken in the direction of arrow 6 in FIG. 1.

It is to be understood that any portion of any figure shown in broken lines are for environmental purposes only and form no part of the claimed design.
